Letters Patent No 2160 - Dated Aug 8-1865.

Design for a Trade Mark

The schedule referred to in these Letters Patent and marking part of the same.

and Persons to whom these Letters Patent will come:

Be it known that George Hesmer of Boston in the County of Suffolk and State of Massachusetts, have invented or produced a new and ornamental design for a Trade Mark or Label; and to hereby declare the same to be fully described in the following specification and represented in the accompanying drawing.

The design is composed of three circular shields enclosed within an ornamental border of leaves. In the upper shield is the letter H, while in the lower shield is the letter K, the conjunction symbol "U" being placed in the middle shield. The upper shield is surrounded by an elongated tablet containing the words "invented by".

On the inner shield there is a circle of stars, the whole being as represented in the drawing.

I claim the said design for a Trade Mark or Label as exhibited in the drawing herewith presented and as above explained.
